United States Patent Office

Des. 184,628
Patented Mar. 17, 1959

184,628

BOOKMARK

Gerald S. Lazarus, Bethpage, N. Y., assignor to Tri Square Products Inc., Kings, N. Y.

Application May 27, 1958, Serial No. 51,103

Term of patent 3½ years

(Cl. D6—2)

Fig. 1 is a front elevational view of a bookmark showing my new design, the opposite side thereof being plain and unornamented; and

Fig. 2 is a side view thereof.

I claim:

The ornamental design for a bookmark, substantially as shown and described.
